CIRCUIT CONTROLLING DEVICE

Ture Lindstrom, Edgewood, Pa., assignor to Westinghouse Electric & Manufacturing Company, East Pittsburgh, Pa., a corporation of Pennsylvania

Application February 5, 1937, Serial No. 124,253

13 Claims. (Cl. 200—106)

My invention relates to electrical control devices in general, and more particularly to trip devices for circuit breakers.

The usual forms of trip devices that have heretofore been used in connection with circuit breakers have consisted in general of a movable latch and/or trip bar for normally restraining the spring biased contact opening or actuating member of the circuit breaker, and an armature biased to a normal position and movable to an attracted position by an abnormal condition responsive electromagnet for moving the latch and/or trip bar to a tripping position to release the actuating member.

In moderate and large size circuit breakers, considerable force is required to trip the breakers and the spring means for biasing the armature to its normal or inoperative position exerts a relatively large force on the armature opposing movement of the same. The force exerted by the spring biasing means increases as the armature is moved to attracted or operative position so that the largest portion of the tractive force exerted by the electromagnet in moving the armature to attracted position is used up in overcoming the resistance of the spring biasing means. Thus only a relatively small portion of the force exerted by the electromagnet is available for performing the work involved in moving the latch means and/or the trip bar to tripping position. This condition becomes even a greater problem in the case of shock-proof circuit breakers because in such breakers even stronger springs must be used to bias both the latch and/or trip bar, and the armature to their normal positions in order to prevent these elements from being moved to trip the breaker by jarring forces or vibrations.

It is accordingly an object of my invention to provide an improved trip device for a circuit breaker in which a maximum portion of the over-load tripping force exerted on the trip actuating member is rendered available to perform the work involved in tripping the breaker.

Another object of my invention is to provide an improved shock-proof trip device for a circuit breaker.

Another object of my invention is to provide a trip device for a circuit breaker with a novel and improved means for restraining the trip actuating member of the trip device in its normal or inoperative position.

Another object of my invention is to provide an improved trip device for a circuit breaker, in which the trip actuating member is rendered

shock proof and in which a maximum amount of the tripping force exerted on said actuating member is rendered available to perform the work involved in tripping the breaker.

Another object of my invention is to provide an electromagnetic trip device for a circuit breaker embodying a trip actuating armature with a novel means for restraining the armature in normal or inoperative position to render the same substantially shock proof, in which the restraining force decreases rapidly as the armature moves toward attracted position whereby a maximum portion of the tripping force exerted on the armature is rendered available to perform the work involved in tripping the breaker.

The novel features that I consider characteristic of my invention are set forth in particular in the appended claims, the invention itself, however, both as to structure and operation, together with additional objects and advantages thereof will best be understood from the following detailed description of a specific embodiment thereof when read in connection with the accompanying drawings, in which

Figure 1 is a plan view of the circuit breaker embodying the features of my invention, the cover of the circuit breaker having been removed.

Fig. 2 is a vertical sectional view of the circuit breaker shown in Fig. 1, taken on the line II—II thereof and looking in the direction of the arrows, the cover being shown in mounted position.

Fig. 3 is a vertical sectional view of the trip device of the circuit breaker taken on the line III—III of Fig. 5.

Fig. 4 is a vertical sectional view of the trip device of the circuit breaker taken on the line IV—IV of Fig. 5.

Fig. 5 is an elevational view of the trip device.

Fig. 6 is a force-distance curve showing the work available for tripping the breaker when relatively strong springs are used for biasing the armature to attracted position, and

Fig. 7 is a similar force-distance curve showing the work available for tripping the same breaker when the trip device embodying the features of my invention is used.

The invention has been shown in connection with a particular form of multi-pole circuit breaker for illustrative purposes only. It will be understood, however, from the following description that the invention is capable of more or less general application to various other forms of circuit controlling devices and electrical devices.

Since the invention is particularly concerned with the electro-responsive trip device and since the circuit breaker wherein my invention has been embodied is completely described in the copending application of Harry J. Lingal, Serial No. 637,749, filed October 14, 1932, and assigned to the assignee of this invention, which became Patent No. 2,083,305 on June 8, 1937, the description of the breaker will be limited to setting forth the various elements. It will be noted that the reference numerals for this case coincide with the reference numerals for Serial No. 637,749. This has been done to facilitate a comparison thereof.

Referring to the drawings, the base 1 is of molded insulating material and has mounted thereon terminal contacts 3 and 5, the removable unitary trip device 7, the circuit breaker operating mechanism 9 which has associated therewith the assemblage of the switch members 11, the arc extinguishers 13, and the stationary contact assemblages 15 of the switch members. The assemblage of the switch members 11 and the stationary contact assemblages 15 combine to form a plurality of poles. Each of the poles is insulated from the adjacent pole by means of insulating barriers 17 (Figs. 1 and 2) which are molded into the base 1. These insulating barriers 17 are adapted to align with similar shaped barriers 21 molded in the cover 19 which is likewise of insulating material. The operating member 23 has a removable handle 25 and is pivoted to the main frame 41 of the operating mechanism 9. An opening 27 is provided in the cover 19 to accommodate the operating handle. The trip device 7 is mounted in position by the screw fastenings 31 and 33 which also serve to electrically connect the terminals 35 and 37 of the trip device with the laminated shunts 39 and the terminals 5 respectively.

The electrical circuit for each of the poles is substantially the same. Beginning with the terminal 3, the current passes successively along the arc extinguishing structure 13, thence through the main stationary contact 16, the co-operating main moving contact 18 and the flexible shunt 39 which is associated with each of the switch members, the terminal 35 of the trip structure 7, and finally through the trip structure to the other terminal 5.

The assemblage of the switch members 11 is pivoted to the main frame 41 of the operating mechanism 9 by means of a pin 42. A steel tie bar 43 serves to rigidly mechanically interconnect the three switch members 11, there being only one pivot point. Each of the switch members 11 includes a clamp member 45 for engaging the tie bar 43. The clamp members are secured to the tie bar by means of bolts 47 or any other suitable form of securing means. A square tube 48 of insulating material is disposed between the tie bar 43 and the clamping members 45 to insulate the several poles of the breaker from each other. The main moving contacts 18 are pivoted to the clamp members 45 through the agency of pivot pins 49. A projecting auxiliary contact member 51 is provided for engaging the stationary arcing contact 53. Springs 55 are provided for biasing each of the main moving contact members 18 toward the cooperating main stationary contact member 16 with a predetermined normal force.

The end of each of the shunts 39 adjacent the switch members 11 is secured to the pivotally mounted contact members 18 through the agency

of rivets 57. Each of the main moving contact members 18 has a rearwardly extending portion 59 for engaging the end of the shunt 39 and for defining the limit of movement of each of the contact members 18 under the biasing action of the contact springs 55. The shunts 39 for the two outer poles are rigidly affixed to the base 1 by means of screw fastenings 61 and 64 which pass through suitable openings in the shunts. The shunt 39 for the central pole is held in place by four screws 62 which engage threaded openings in the base of the main frame 41. The shunts 39 are of laminated construction being built up of a plurality of thin sheets of copper. The clamp member 45 of the central switch member has openings 66 for engaging the contact assemblage pivot pin 42, openings 67 for engaging the breaker operating mechanism, and slotted openings 69 for clearing the pivot pin 75 of the main operating member 23.

Any suitable type of arc extinguishing means may be used. The form illustrated is similar to those shown in Patent No. 1,896,764 of M. W. Brainard issued February 7, 1933, and assigned to the assignee of this invention.

The operating mechanism 9 comprises in general a base or main frame 41, a pair of toggle links 77 and 79, one end of which is connected to the assemblage of switch members 11 through the central clamp member 45, a carrier lever 81 for releasably restraining the other end of the toggle links 77 and 79 in operative position, an operating member 23, an overcenter spring unit 83 for connecting the operating member 23 to the knee of the toggle links, and the operating handle 25.

The base 41 is positioned above the conducting shunt 39 of the central pole and is rigidly affixed to the base by means of the screw 62. One end of the toggle link 77 operatively engages the openings 67 in the central clamping member 45 through the agency of a pivot pin 89. The other end of the toggle link 77 is pivoted to one end of the toggle link 79 by means of a knee pivot pin 91, the toggle links 77 and 79 are provided with portions which engage when the breaker is in the closed position to define the limit of upward movement of the knee of the toggle.

The overcenter spring unit 83 operatively connects the end 95 of the operating member 23 with the knee pivot pin 91 of the toggle links and exerts a tension force therebetween. The overcenter spring unit 83 comprises a frame 96 one end of which is adapted to engage the knee pivot pin 91 and the other end of which has a circular opening to accommodate the plunger member 97. The overcenter spring 98 which is itself in compression is positioned between the end of the frame 96 and the enlarged portion 99 of the plunger 97. The outer end of the plunger 97 pivotally engages the end 95 of the operating member 23 by means of a pin 101 which fits in a suitable recess 102.

The end 103 of the toggle link 79 is provided with a circular bearing portion 104 which engages a suitable recess in the end of the bell crank carrier lever 81. Two retaining plates 105 are disposed on the outer sides of the carrier 81 to prevent the bearing portion 104 from moving sideways and disengaging the recess.

The bell crank carrier lever 81 has a projecting portion 107 for engaging the latching lever 111 and is pivoted to the base 41 at its apex by means of a pivot pin 109. The portion 110 of the carrier 81 extends along the base 41 to form what

might be termed a tail portion. The perpendicular distance from the center of the carrier pivot pin 109 to the line of action of the toggle lever 79 is considerably less than the distance from the center point of the carrier pivot pin 109 to the projecting portion 107 of the carrier 81. This gives the carrier lever 81 an appreciable mechanical advantage over the toggle.

The overcenter spring unit 83 at all times exerts a force on the carrier lever 81 biasing the lever in a clockwise direction and it is to restrain the carrier lever in the operative position that the latching lever 111 is provided.

The latching lever 111 includes a projecting portion 112 for engaging the end of the section 107 of the carrier lever 81, and a portion 113 for engaging the trip latch 150 (see Fig. 4). One end of the latching lever 111 is pivoted to the base 41 by the pivot pin 115 adjacent the point 20 of engagement with the tail piece 110 of the carrier member 81. The projecting portion 112 of the latching lever normally overhangs the end of the portion 107 of the carrier lever 81 and thus holds the carrier in an operative position 25 by preventing it from moving upward. The free end of the latching lever 111 is releasably restrained in the position shown in Fig. 2 by reason of the engagement of the portion 113 with the trip latch 150, which latter forms a part of the trip device 7.

The trip device is of the same general type as that disclosed and claimed in the copending application of Jerome Sandin, Serial No. 123,236, filed January 30, 1937 and assigned to the assignee of this invention; now Patent 2,178,083 issued October 31, 1939. The trip structure 7 is a unitary device entirely assembled upon its own base 153 of molded insulating material and is completely removable from the breaker; the screw 40 fastenings 31 and 33 being utilized to mount the trip structure on the base 1 and to also make the necessary electrical connections. The trip device 7 includes a magnetically responsive element for each of the poles, and the mechanism of the device is so arranged that a heavy overload in the circuit controlled by any one of the poles will actuate the trip mechanism instantaneously to open all of the poles of the breaker.

Each of the trip elements of the trip device are 50 mounted on the trip base 153 through the agency of a metallic yoke 155. The yoke 155 is substantially U-shaped and has a pair of outstanding lugs 157 for pivotally supporting a U-shaped armature 159. The armature 159 is pivotally 55 mounted on the lugs 157 by means of pivot pins 161. Each of the legs of the yoke 155 is provided with an offset angular end portion 163, for supporting a transverse stationary core member 165. The stationary core member 165 is secured to the 60 offset ends 163 of the yoke by means of screw fastenings 167. Each of the armatures 159 is adapted to be biased toward its normal position, as shown in Figs. 3 and 4, by means of a pair of relatively light biasing springs 169. The springs 65 169 are disposed upon studs 171 which are carried by the base 153 of the trip device. One end of each of the springs 169 engages a slidably bushing 173 which is slidably mounted on the stud 171 and the other end of each spring is held in stressed condition by means of a washer 175 and a cotter pin 177. The force exerted by the springs 169 causes the slidably bushings 173 to engage and bias the armatures 159 to their normal position, as shown in Figs. 3 and 4. An energizing conductor 179 is provided for each of the trip

elements. The ends of the conductors form the terminals 35 and 37 of each trip device, and the body portion passes between the legs of the armature 159 and the yoke 155. The energizing conductor 179 and the stationary core 165 form an electromagnetic means for attracting and moving the movable armature 159 to an attracted position against the stationary core 165. The cross piece 181 of non-magnetic material is secured to the ends of the legs of each of the armatures 159 in order to provide a balancing means for the armature so as to render the same less responsive to movement by shock or jarring forces.

In order to provide for accurate positioning of the trip device with respect to the path of movement of the latching lever 111, there is provided a metallic bracket 183 which is rigidly affixed to the center portion of the trip base 153 by means of screw fastenings (not shown). The bracket 183 has a base portion 185 which is of substantially the same outline as the center terminal 35 and is thus adapted to be fastened to the base of the circuit breaker by means of the screw fastenings 31 of the central pole. The central fastenings 31 would probably be sufficient to accurately 20 position the trip device but in order to insure that the position is correct, there is provided an additional positioning means which consists of a projecting male member 187 which extends downwardly (Fig. 4) through a suitable opening in the center terminal 35 and is adapted to engage a cooperating female portion 189 in the center shunt 39; this shunt being securely fastened to the base 1 and accurately positioned with respect to the operating mechanism by means of the 25 screw fastenings 62.

The bracket 183 has an opening 191 in the upper portion, the trip lever 150 being pivotally mounted therein through the agency of a pivot pin 193.

The trip lever 150 is preferably constructed of metal and has a projecting portion 195 for engaging the latch engaging means associated with the latching lever 111. A spring 197 is provided for biasing the trip lever 150 to the latched position, and a notch 199 is provided in the trip lever 45 for engaging the trip bar 201.

The trip bar 201 is of molded insulating material and extends across all three poles of the breaker. It is pivotally supported at two points 50 adjacent and on either side of the trip lever 150 by means of a pair of lugs 203 which project from the base 153 of the trip device. Lugs 203 are provided with openings for the reception of pivot pins 205 carried by the trip bar. Filler screws 207 55 are provided for maintaining the trip bar in pivotally mounted position. The trip bar 201 engages the trip lever 150 through the agency of a bracket 209, one end of which engages the notch 199 and the other end of which is rigidly affixed 60 to the trip bar by a pair of rivets. A compression spring 211 biases the trip bar clockwise (Fig. 4) about its pivot axis to its latched position. Three downwardly extending members 213 each affixed to the trip bar by means of a rivet 65 are provided for engagement by the armatures 159 of each of the magnetically responsive elements of the trip device. A cover 215 is positioned on the trip base in order to protect and enclose the various elements of the trip device. 70

The portion 113 of the latching lever 111 includes a bifurcated projection 217 which pivotally supports a latch engaging lever 219 through the agency of a pivot pin 221. The latch engaging lever 219 is biased into engaging position by a 75

spring 223 and its movement in a clockwise direction is limited by the base portion of the bifurcated projection 217.

The trip bar 201 and the members carried thereby are so constructed that the trip bar is both statically and dynamically balanced in order to render the same substantially shock proof. The positioning of the pivot means of the trip bar on either side of and adjacent the latch load 10 prevents any flexing of the trip bar which would tend to throw the same out of balance.

In the type of trip device disclosed in the co-pending application of Jerome Sandin, Serial No. 123,236, referred to above, relatively strong biasing springs are used for biasing the armatures to their normal position in order to render the same substantially shock proof. While this arrangement has the advantage of rendering the armatures substantially shock proof so that they 15 will not be moved by a jarring force to cause tripping of the breaker, an inherent disadvantage is present. When the springs are made relatively strong, substantially the greatest portion of the force exerted by the electromagnetic means including the energizing conductor and the stationary core is absorbed or used up in overcoming the resistance of the relatively strong biasing springs and only a small portion of the force is rendered available for performing the work necessary to move the latches and trip the breaker.

By my invention, I have provided a biasing means for the armature which renders the same substantially shock proof and at the same time permits a maximum portion of the force exerted by the electromagnetic means to be rendered available for the purpose of performing the work necessary to trip the breaker. To accomplish the above stated function, the springs 169 are constructed of relatively fine wire with a large 20 number of turns so that these springs exert a relatively small biasing force sufficient to return the armature to normal position following de-energization of the electromagnetic means after the same has moved the armature to its attract- 25 ed position. In combination with the relatively light springs 169, a stationary plate 225 of magnetic material is mounted on the yoke 155 of each of the electro-responsive trip elements. The armature 159 is provided with a small air gap 30 or a small insert of non-magnetic material 221 adjacent the plate 225 as shown in Fig. 5. When the circuit breaker is closed the current flowing through the energizing conductor 179 produces a circular magnetic field about the conductor 35 179 which in turn produces a magnetic flux in the armature 159 and the core 165. The flux produced would ordinarily, without the presence of the plate 225 and the gap 221, flow through the armature 159 and core 165 and across the air 40 gaps between the ends of the armature 159 and the core 165. The gap 221, however, shunts a portion of the magnetic flux through the plate 225. The flux thus produced in the plate 225 creates a magnetic attracting force between the 45 armature 159 and the plate 225 which acts to restrain the armature in its normal position, shown in Figs. 3 and 4, with a predetermined force. The plates 225 are dimensioned so as to become saturated at normal current values or at 50 current values slightly above normal so that the attractive force between the plates and the armatures becomes a maximum at such current values. This attractive or restraining force is sufficient 55 to prevent the armatures 159 from being moved toward attracted position in response to jarring

forces or heavy vibrations applied to the base of the breaker. If a heavy magnitude overload occurs, the flux produced in the armature 159 and the stationary core 165 becomes sufficient to move the armature to its attracted position. As the 5 armature is moved toward attracted position, the restraining flux force exerted between the plate 225 and the armature 159 decreases rapidly and becomes substantially zero after the armature has been moved a small portion of the distance 10 toward attracted position. After the armature has moved a small portion of the distance toward attracted position, the only restraining force tending to prevent movement of the armature is the small force exerted by the relatively weak 15 springs 169 so that a maximum portion of the pull of the electromagnetic means is rendered available for the purpose of overcoming the latch load of the circuit breaker.

Fig. 6 illustrates a force-distance curve for a 20 circuit breaker which does not embody the features of my invention but which utilizes relatively strong springs for biasing the armature to its normal position. The contour A represents the trip force produced by the magnetic flux during an overload. The contour B represents the resisting force produced by the relatively strong biasing springs. I represents the initial or normal position of the movable armature and F represents the final or trip position of the movable armature. L represents the travel of the movable armature or the air gap between the movable armature and the stationary core. The area W₁ represents the work available to release the trigger and Y represents the trip force necessary to start movement of the armature. It will be noted from Fig. 6 that a relatively small amount of work represented by the area W₁ is available for actually performing the work of tripping the breaker because of the fact that a 40 large portion of the force produced by the magnetic flux is used up in overcoming the resistance of the strong biasing springs.

Fig. 7 illustrates a force-distance curve with a circuit breaker when the same is equipped with a trip device embodying the features of my invention. Referring to Fig. 7, the contour A₁ represents the trip force produced by the magnetic flux on overload and is the same as in Fig. 6. The contour C represents the force 50 exerted by the relatively weak springs 169 which bias the armature toward its normal position. The contour D represents the restraining force produced by the magnetic flux between the magnetic plate 225 and the armature 159. The contour B₁ is the sum of C and D and shows the combined force produced by the relatively weak biasing springs 169 and the flux force produced by the magnetic plate 225. The area W₂ represents the work available for overcoming the latch 55 load of the circuit breaker. The point I represents the initial or normal position of the armature and the point F represents the final or tripped position of the movable armature. L represents the travel of the movable armature or the air gap between the armature 159 and the stationary core 165. Y represents the trip force necessary to start moving the armature. It will be noted from Fig. 7 that a considerably larger 60 amount of work is rendered available for actually tripping the breaker (represented by the area W₂) when a trip device embodying the features of my invention is used, than in the case of a trip device embodying relatively strong biasing 65 70 75

springs for biasing the armature to normal position and rendering the same shock proof.

The exact details of operation of the circuit breaker mechanism 9 are set forth in the previously mentioned application of Harry J. Lingal and the disposition of the various parts of the mechanism in the open, closed and the tripped position are shown in the drawings accompanying that application. Generally however, the operation is as follows. To manually move the contacts from the closed position shown in Fig. 2 to the open position, the handle 25 is moved downwardly. This downward movement causes the toggle links 17 and 79 to collapse toward the base 1 under the influence of the overcenter spring unit 83. The collapse of the toggle causes the entire assemblage of the switch members 11 to pivot about the pin 42 and move to the open position with a snap action. To close the contacts manually, the operation is reversed, the handle 25 is moved upwardly and the toggle is restored to the position shown in Fig. 2 by the force exerted by the overcenter spring unit. The contacts close as well as open with a snap action due to the progressive acceleration given by the toggle.

When the circuit breaker is in the closed circuit position (Fig. 2) and an overload of sufficient magnitude to actuate the trip device occurs in the circuit controlled by any one of the poles of the breaker; the latching lever 150 is released by the movement of trip bar 201 to effect release of the free end of the latching lever 111. The latching lever 111 is biased counterclockwise (Fig. 2) about its pivot pin 115, and as soon as it is released it moves so that the portion 112 thereof uncovers the cooperating end portion 167 of the tail member 116 of the carrier lever 81. The entire mechanism is now free to move under the biasing action of the contact springs 56. These springs cause the assemblage of the switch members to move counterclockwise about the pivot pin 42, and at the same time cause the toggle links 17 to be moved toward the base of the circuit breaker. The combined result of these movements is to cause a clockwise movement of the carrier lever 81 and a collapse of the toggle links toward the base 1 due to the bringing of the center line of the overcenter spring unit 83 below the center line of the toggle link 79. The circuit breaker operating mechanism is completely resettable by means associated with the operating member 23.

The operation of the trip device is substantially as follows. Upon the occurrence of an overload in the circuit controlled by any one of the poles of the breaker, the energization of the stationary core 165 and armature 159 reaches a sufficient magnitude to overcome the restraining force exerted on the movable armature by the magnetic plate 225 and the biasing springs 169, and to move the armature 159 to its attracted position. The movement of the armature 159 to its attracted position toward the stationary core 165 causes the armature to engage the downwardly extending member 210 and move the same so as to cause counterclockwise rotation of the trip bar 201. The counterclockwise rotation of the trip bar 201 causes the bracket 209 carried thereby to release the latch lever 150 thus permitting the latch engaging lever 219 affixed to the free end of the latching lever 111 to disengage the projection 195 on the latch lever 150. The free end of the latching lever 111 is biased away from the base by the operating mechanism itself, and

it, therefore, immediately moves to the tripped position thereby causing the contacts of the breaker to open. As soon as the latch engaging lever 219 has disengaged the projection 195 on the latch 150, the biasing spring 197 restores the latch 150 to latched position shown in Fig. 4.

The provision of magnetic plate 225 for restraining the armature 159 in its normal position with a predetermined force renders the armature substantially shock proof so that any tendency of the same to be moved by a jarring force or vibration is prevented. The provision of the magnetic plate 225 also permits the use of relatively weak biasing springs 169 for biasing the armature toward its normal position and since the flux force produced by the magnetic plate 225 which acts to restrain the armature decreases rapidly as the armature is moved toward attracted position, a maximum portion of the force exerted by the electro-responsive trip means is rendered available for moving the latches to their released position.

While the novel means for restraining the armature in its normal position cooperates with the remaining structure of the trip device in that all of the moving parts which might cause tripping of the breaker are rendered substantially shock proof, it is to be understood that the principles of my invention are applicable to other forms of trip devices, circuit interrupters, or electrical devices.

I have given the foregoing details of a practical embodiment of my invention in accordance with the patent statutes. It is to be understood, however, that various changes in the structure may be made without departing from the spirit of my invention. I desire, therefore, that the invention be limited only by the reasonable construction of the appended claims and by the prior art.

I claim as my invention:

1. In a circuit breaker having relatively movable contacts, operating mechanism for opening and for closing said contacts, and a spring-biased actuating member releasable to effect opening of said contacts; a trip device comprising releasable latch means for restraining said actuating member, an armature movable from a normal unattracted position to an attracted position to effect release of said latch means to free said actuating member, an electromagnet connected in circuit with said contacts operable in response to overload currents of more than a predetermined magnitude to move said armature to attracted position, and means including a member of magnetic material positioned adjacent said armature in its normal position for restraining said armature in its normal position with a predetermined force, said armature having a portion of increased reluctance adjacent said member of magnetic material for causing a portion of the magnetic flux to be shunted through said member, and said member being arranged to become saturated at a current below said predetermined magnitude, whereby said armature is rendered substantially shock proof, and whereby a large portion of the force exerted by said electromagnetic means on overload becomes available for effecting release of said latch means during movement of said armature to tripping position.

2. In a circuit breaker having relatively movable contacts, operating mechanism for opening and for closing said contacts, and a spring biased actuating member releasable to effect opening of said contacts; a trip device comprising releasable holding means for restraining said actuating

member, an armature movable from a normal position to an attracted position to effect release of said holding means, an electromagnet connected in circuit with said contacts operable in response to predetermined overload conditions to move said armature to attracted position to effect release of said holding means to free said actuating member, a member of magnetic material disposed adjacent said armature in its normal position for restraining said armature in its normal position with a predetermined force, said armature being provided with a gap adjacent said member so that a portion of the flux produced in said armature is shunted around the gap by said member, said member being constructed so as to become saturated at normal current values.

3. In a circuit breaker having relatively movable contacts, operating mechanism for opening and for closing said contacts, and a spring biased actuating member releasable to effect opening of said contacts; a trip device comprising releasable holding means for normally restraining said actuating member, electromagnetic means including a pivoted armature movable from a normal position to an attracted position to effect release of said holding means to free said actuating member, a core of magnetic material and an energizing winding connected in circuit with said contacts operable in response to predetermined overload conditions to move said armature to attracted position, a member of magnetic material disposed adjacent said armature in its attracted position arranged to become saturated at normal current value, said armature having a portion of greater reluctance adjacent said member for causing a portion of the magnetic flux to be shunted through said member, said member restraining said armature in its normal position with a predetermined force to render the same substantially shock proof; and relatively light springs for biasing said armature to normal position.

4. A control device for electrical apparatus comprising an armature movable from a normal position to an attracted position to operate said apparatus, electromagnetic means for said armature operable in response to currents of more than a predetermined magnitude to move said armature to attracted position, and a member of magnetic material positioned adjacent said armature in its normal position, said armature having a portion of greater reluctance adjacent said member for causing a portion of the magnetic flux to be shunted through said member, and said member being arranged to become saturated at a current value below said predetermined magnitude, whereby said member restrains said armature in its normal position with a predetermined force.

5. A trip device for a circuit breaker comprising an armature movable from a normal position to an attracted position to effect tripping of said breaker, electromagnetic means for said armature energized by the circuit controlled by the breaker and operable in response to predetermined abnormal conditions to move said armature to attracted position, a member of magnetic material mounted adjacent said armature in its normal position said armature being provided with a portion of non-magnetic material adjacent said member so that said member shunts a portion of the flux produced in said armature, said member being arranged to become saturated at normal current values whereby it restrains said

armature in its normal position with a predetermined force; and relatively weak spring means for biasing said armature to its normal position.

6. A trip device for a circuit breaker comprising an armature movable from a normal position to an attracted position to effect tripping of said breaker, electromagnetic means for said armature energized by the circuit controlled by the breaker and operable in response to predetermined abnormal conditions to move said armature to attracted position, a member of magnetic material mounted adjacent said armature in its normal position, said armature being provided with a gap adjacent said member so that said member shunts a portion of the flux produced in said armature, said member being arranged to become saturated at normal current values whereby it restrains said armature in its normal position with a predetermined force.

7. In a circuit interrupter having relatively movable contacts, electromagnetic trip means operable in response to predetermined conditions to cause opening of said contacts comprising a core of magnetic material and a movable armature forming a substantially closed magnetic circuit having at least one air gap between the armature and the core when the armature is in normal unattracted position, and an energizing conductor connected in circuit with said contacts, said armature being movable from a normal unattracted position to an attracted position in response to predetermined conditions to cause opening of said contacts, and a member of magnetic material mounted adjacent said armature and included in the magnetic circuit when the armature is in its normal position for restraining said armature in its normal position with a predetermined force, said armature having a portion of increased reluctance adjacent said member for causing a portion of the magnetic flux to be shunted through said member.

8. In a circuit breaker, relatively movable contacts biased to open circuit position, releasable latch means for latching said contacts in closed circuit position, electromagnetic trip means comprising a core of magnetic material and a movable armature of magnetic material forming a substantially closed magnetic circuit having at least one air gap between the armature and core when the armature is in normal unattracted position, and an energizing conductor connected in circuit with said contacts, said armature being movable from its normal position to an attracted position in response to predetermined conditions to effect release of said latch means and opening of said contacts, and a member of magnetic material mounted adjacent said armature and included in the magnetic circuit when the armature is in its normal position for restraining said armature in its normal position with a predetermined force to prevent said armature from being moved to attracted position by shocks or jarring forces, said armature having a portion of increased reluctance adjacent said member for causing a portion of the magnetic flux to be shunted through said member.

9. In a circuit breaker relatively movable contact means, operating means for opening and closing said contacts including a spring biased actuating member releasable to cause opening of said contacts, electromagnetic trip means operable in response to predetermined conditions to release said actuating member to cause opening of said contacts comprising a core of magnetic material and a movable armature forming a sub-

stantially closed magnetic circuit having at least one air gap between the armature and the core when the armature is in normal unattracted position, and an energizing conductor connected in circuit with said contacts, said armature being movable to an attracted position to effect release of said actuating member, and means including a member of magnetic material mounted adjacent said armature and included in the magnetic circuit when the armature is in its normal position for restraining said armature in its normal position with a force sufficient to prevent said armature from being moved to attracted position by shocks or jarring forces, said armature having a portion of greater reluctance adjacent said member of magnetic material for causing a portion of the magnetic flux to be shunted through said member, the restraining force exerted by said member of magnetic material decreasing rapidly as said armature is moved toward attracted position in response to said predetermined conditions whereby a large portion of the force exerted by said electromagnetic means becomes available for tripping the breaker during movement of said armature toward attracted position.

10. An electromagnetic trip device for a circuit breaker comprising a core of magnetic material and a movable armature of magnetic material forming a substantially closed magnetic circuit having at least one air gap between the armature and the core when the armature is in normal unattracted position, said armature being movable from its normal position to an attracted position in response to predetermined conditions to trip said breaker, and a member of magnetic material mounted adjacent said armature and included in the magnetic circuit when the armature is in its normal position for restraining said armature in its normal position with a predetermined force, said armature having a portion of greater reluctance adjacent said member of magnetic material for causing a portion of the magnetic flux to be shunted through said member.

11. An electromagnetic trip device for a circuit breaker comprising a core of magnetic material and a movable armature of magnetic material forming a substantially closed magnetic circuit having at least one air gap between the armature and the core when the armature is in normal unattracted position, said armature being movable

from its normal position to an attracted position in response to predetermined conditions to trip said breaker, and a member of magnetic material mounted adjacent said armature and included in the magnetic circuit when the armature is in its normal position for restraining said armature in its normal position with a predetermined force sufficient to prevent said armature from being moved toward attracted position to falsely trip said breaker by shocks or jarring forces, said armature having a portion of greater reluctance adjacent said member of magnetic material for causing a portion of the magnetic flux to be shunted through said member; and relatively weak spring means biasing said armature to its normal position.

12. An electromagnetic trip device for a circuit breaker comprising a core of magnetic material and a movable armature of magnetic material forming a substantially closed magnetic circuit having at least one air gap between the armature and the core when the armature is in normal unattracted position, said armature being movable from its normal position to an attracted position in response to predetermined conditions to trip said breaker, a member of magnetic material mounted adjacent said armature, said armature being provided with a gap adjacent said member so that a portion of the magnetic flux produced in said armature is shunted through said magnetic member to cause said member to restrain said armature in its normal position with a predetermined force.

13. An electromagnetic trip device for a circuit breaker comprising a U shaped movable armature and a core of magnetic material mounted adjacent the ends of said armature forming a substantially closed magnetic circuit, an energizing conductor threading said core and armature, said armature being movable from a normal position to an attracted position in response to predetermined conditions to trip said breaker, and a member of magnetic material mounted adjacent said armature and included in the magnetic circuit when the armature is in its normal position for restraining said armature in its normal position with a predetermined force, said armature having a portion of greater reluctance adjacent said member of magnetic material for causing a portion of the magnetic flux to be shunted through said member.
